UNITED STATES PATENT OFFICE

PATRICK H. WALSH, OF WESTERLY, RHODE ISLAND, ASSIGNOR TO CARO CLOTH CORPORATION, OF CAROLINA, RHODE ISLAND, A CORPORATION OF DELAWARE

SELF-CLEANER FOR CARDS

Application filed October 11, 1928. Serial No. 311,865.

My present invention relates to textile machinery, and more particularly to an improved cleaning device for carding rolls and the like.

In the use of carding machinery, considerable difficulty has heretofore been experienced in maintaining the carding rolls free of foreign substances. Heretofore, it has been practically impossible to maintain the carding rolls in clean condition and it has been necessary to periodically dismantle the machine by taking off the working and other rolls and clean the card clothing thereon manually, which is a slow and very expensive process. The applicant in his development of improved apparatus for and processes of manufacturing textile fabrics has utilized carding machines as an integral part of his device for practicing a continual process of manufacturing textile fabrics by an entirely new process. Difficulty was experienced, as is usual, in maintaining the carding rolls clear of foreign substances and when it became necessary to clean the rolls manually by dismantling the carding machines, necessarily the entire process devised by the inventor, became for the moment inoperative, it thus being necessary to shut down the entire mill until such time as the carding machines could be placed back in operation again.

With a view to obviating the objections above noted and to devise a cleaning device which would be automatic in its operation, and thus enable the carding machine to operate continuously and continually in carrying out applicant's improved process, there was devised the subject matter of the present invention. As is well known, carding rolls may be built in a plurality of ways, one of which, the most advantageous for the type of carding machine employed by the applicant, is to wrap about a cylinder in a helical form a ribbon of metal or other suitable material, provided on one edge with a series of teeth. The teeth taper in thickness from the full width of the ribbon of metal down to a point and when the ribbon is wound in a helical manner on the cylinder, there is necessarily formed a helical groove extending through-

out the entire length of the cylinder. It is in this helical groove that the foreign substance collects and gradually builds up until the teeth of the card clothing no longer have the efficiency necessary. In order to provide a cleaner which will be self-actuating, I have provided a shaft arranged parallel to the shaft of the carding roll with which the same is to be associated and on such shaft I arrange a freely movable member provided with a downwardly depending tooth which fits into the helical groove formed by the ribbon of metal on the carding cylinder. It was found that while such a construction enabled the tooth to follow along in the helical groove, yet it was subject to sticking, and in order to overcome the same, I found it advantageous to positively drive the shaft on which the cleaning device was located, even though such device was freely movable on the shaft. The rotation of the shaft reduced the friction between the same and the cleaning device to such an extent that it is now found that the cleaning device and the tooth attached thereto follows freely along the shaft as the carding roll rotates.

The object of my invention, therefore, is an improved cleaning device for carding rolls and the like.

In the accompanying drawings,

Fig. 1 illustrates my invention applied to a carding machine, and

Fig. 2 is a section on the line 2-2 of Fig. 1.

Referring to the drawings, there is shown the usual carding machine comprising a base 10 having rotatably mounted therein a shaft 11, on which is mounted the work cylinder 12 provided with the ordinary card clothing 13. Associated with the work cylinder 12 are a plurality of work rolls 14 as is usual. Also associated with the work roll 12 is a breaker roll 15 rotatably mounted on a shaft 16 arranged parallel to the shaft 11. The breaker roll 15 is provided with a card clothing 17 and I have shown my invention in association with such card clothing.

Referring to Fig. 2, it will be seen that the cylinder 15 has wrapped thereon the card

clothing 17, such card clothing comprising a ribbon of indeterminate length, provided with teeth on one edge and arranged in a helical manner on the cylinder 15. As the cylinder 15 rotates it is obvious that if a pointed tooth is placed in the space between adjacent turns of the ribbon forming the card clothing 17 and the cylinder 15 rotated, that such tooth will dig out of the groove any foreign substance that may be lodged therein. In order to provide that this operation may be performed mechanically, I provide on the framework 10 of the carding machine auxiliary frames 18 in which is rotatably mounted a shaft 19 arranged parallel to the shaft 16. I have also secured to the shaft 16 a gear 20 which meshes with and drives a gear 21 secured to the shaft 19. The gears 20 and 21 are so arranged that the speed of rotation of the shaft 19 is slightly greater than the speed of rotation of the shaft 16, although the device will work well regardless of the ratio of speed between such shafts 16 and 19. Rotatably and slidably mounted on the shaft 19 is a member 22 provided on one side with a counter-balancing weight 23, which weight will always tend to remain under or below the shaft 19, and secured to such overbalancing weight 23 is a cleaning pin or tooth 24, preferably of spring steel or equivalent substance, and pointed at its end so as to enter the helical grooves between the adjacent turns of the ribbon forming the card clothing 17.

Assuming that the breaker roll 15 is rotating in the direction of the arrow shown in Fig. 1, and, therefore, the shaft 19 to be rotating in the direction of the arrow shown, and that the cleaning tooth 24 has been placed in a groove between adjacent turns of the ribbon forming the card clothing 17, then it is obvious that as the cylinder 15 rotates, the tooth 24 will move from left to right, as viewed in Fig. 2, and that the cleaning tooth 24 always remaining in the helical groove, such groove will have removed therefrom any foreign substance that may have collected therein. When the cleaning tooth 24 has reached the right-hand end of the cylinder 15, as viewed in Fig. 2, the operator may lift the tooth upward so as to clear the clothing 17 and slide the member 22 to the left again, as viewed in Fig. 2, and start the device in operation again. It is obvious, of course, that the operation of the tooth 24, as concerns its return to initial operating position, may be performed automatically, but as, on the usual card it is a matter of several hours before the tooth 24 will traverse the length of the cylinder 15, it has not been thought necessary to show such automatic structure.

Having thus described my invention, what I claim as new is:

1. In a device of the kind described, the combination with a breaker roll provided with clothing thereon arranged in helical

form, of a cleaning device engaging therewith, a support on which said cleaning device is rotatably mounted to permit movement of the cleaning device thereon on rotation of the breaker roll.

2. In a device for automatically cleaning card clothing arranged in helical form on a cylinder, the combination of a shaft, means for rotating said shaft simultaneously with the rotation of the carding cylinder, a tool holder rotatably and slidably mounted on said shaft, and a cleaning tooth on said member engaging in a helical groove in the card clothing.

3. In a device for automatically cleaning card clothing, of a carding cylinder comprising a shaft, means for rotating the same simultaneously with the rotation of the carding cylinder, a member freely movable on said shaft, a counter-balancing weight arranged at one side thereof, a cleaning tooth of spring material associated with said counter weight, and extending into the helical groove formed by the card clothing, whereby the supporting member will be freely movable along the shaft on which it is mounted.

In testimony whereof, I have signed my name to this specification.

PATRICK H. WALSH.
